UNITED STATES PATENT OFFICE

2,541,251

PORTABLE ELECTRIC FAN

Friedrich Honerkamp, Woodside, N. Y., and Leonard R. Phillips, Teaneck, N. J., assignors to Anemostat Corporation of America, New York, N. Y., a corporation of Delaware.

Application April 29, 1948, Serial No. 23,928

4 Claims. (Cl. 219—39)

1

This invention relates to portable electric fans, and has for one of its objects to provide a portable electric fan which is of distinctive, attractive appearance and in which moving parts such as the motor and the fan blades are concealed from view.

Another object of the invention is to provide a portable electric fan including an air circulating unit and a combined support and handle therefor combined therewith in a novel manner.

Another object of the invention is to provide a portable electric fan including an air circulating unit and a casing therefor combined therewith in a novel manner.

Another object of the invention is to provide a portable electric fan including novel means for supplying to the air circulated by the same a vapor for air scenting, deodorizing or other purposes.

Another object of the invention is to provide a portable electric fan including means for filtering, heating and subjecting to the action of a germicidal lamp the air circulated by the same.

Another object of the invention is to provide a portable electric lamp in which the means mentioned are assembled in a practical, compact manner and in which the various different elements comprising the complete fan assembly are designed to facilitate their manufacture and assembly.

With the foregoing and other objects in view, which will become more fully apparent as the nature of the invention is better understood, the same consists in a portable electric fan embodying the novel features of construction, combination and arrangement of parts as are illustrated by way of example in the accompanying drawings and as will be hereinafter more fully described and claimed.

In the accompanying drawings, wherein like characters of reference denote corresponding parts in the different views:

Fig. 1 is a central, longitudinal section through a portable electric fan constructed in accordance with the invention.

Fig. 2 is a view partly in top plan and partly in horizontal section of the fan.

Fig. 3 is a transverse section on the line 3—3 of Fig. 1.

Fig. 4 is a transverse section on the line 4—4 of Fig. 1; and

Fig. 5 is a rear elevation of the fan.

Referring to the drawings in detail, it will be observed that the present fan comprises, generally speaking, an air circulating unit, desig-

nated generally as A, and a support therefor, designated generally as B.

While the unit A may be of any suitable type, it preferably is of the axial flow type comprising a motor housing 10; an open-ended annular member 11 surrounding said motor housing and connected thereto by air flow directing vanes 12; an electric motor 13 mounted in said motor housing, and blades 14 driven by said motor for circulating air forwardly through said annular member 11.

In accordance with the invention an open-ended tubular member 15 of sheet metal or other suitable material is suitably secured at its front 15 end to the rear end of the annular member 11 and extends rearwardly from the latter in axial alignment therewith, constituting, in effect, a rearward extension of said annular member 11.

In the tubular member 15 is suitably mounted 20 an electrical heating element 16 of any suitable type for heating air flowing through said tubular member. Also suitably mounted in said tubular member 15 is a bracket 17 which carries a base 18 for a germicidal lamp 19 which, when 25 energized, is effective to destroy harmful germs which may be contained in air flowing through said tubular member. A starter 20 and a ballast element 21 for said lamp 19 also are carried by the bracket 17.

Enclosing the unit A and the tubular member 15 is a casing 22 which is composed of separate front and rear portions 23 and 24, respectively, the front end portion of the former of which is inturned and engaged over the front end portion of the annular member 11 whereby it is supported by said annular member, and the rear portion of the latter of which is engaged over the rear end of the tubular member 15 whereby it is supported by said tubular member. At their adjacent ends, said portions 23 and 24 35 may be engaged one over the other and may be detachably connected together by screws 25 or in any other suitable manner. In any event, due to the casing 22 being divided into front and rear sections, the same may be produced readily and easily and may equally readily and easily be assembled in enclosing relationship to the unit A and the tubular member 15.

In the casing 22, preferably at the bottom thereof, is mounted a switch 26 for controlling the motor 13 and the heating element 16, and a switch 27 for controlling the germicidal lamp 19.

The casing 22 is open at its front and rear ends and at its front end carries a plurality of

open-ended, hollow, flaring, annular members 28 which are spaced apart to provide a plurality of flaring air passageways *a* therebetween. Air circulated by the unit A is delivered from the device through the passageways *a* in a plurality of separate flaring streams whereby it is diffused and creates little or no sensation of draft.

At the rear end of the casing 22 is a louver unit 29 which is composed of a plurality of open-ended annular members 30 which are spaced from the casing 22 and from each other to provide a plurality of annular passageways *b* for inlet of air to the fan. The members 30 are joined together in a unitary assembly by a plurality of arms 31 which extend into the rear portion of the casing 22 and are detachably connected thereto by screws 32 or by any other suitable means. Thus, said louver unit may readily be attached to and detached from said casing 22.

In the louver unit 29 is mounted suitable means 33 to filter air entering the rear end of the casing 22 through the passageways *b* in said louver unit, said means comprising, for example, a layer of spun glass fibres or other suitable material suitably mounted upon a screen 34 or other foraminous member which may be suitably mounted as, for example, upon the arms 31.

Constituting part of the louver unit 29 and disposed centrally thereof is a container 35 for a vaporizable material for air scenting, air deodorizing or any other desired purpose. In the container may be a body of absorbent material 36 to be saturated by the vaporizable material in the event the latter is of liquid form. However, the said vaporizable material may be of solid, granular or other form, in which event the absorbent material 36 is unnecessary.

The container 35 includes outer and inner walls 37 and 38, respectively, having therein openings 39 and 40, respectively, for circulation of air through said container. To regulate flow of air through said openings and hence through said container, a valve member 41 is disposed against the outer face of the outer wall 37 and is rotatable to cover and uncover the openings 39 in said outer wall. A stem 42 extends inwardly from said valve member through the container 35 and through an arm 43 of the bracket 17 and inwardly of said bracket arm is provided with a nut 44 or other suitable abutment between which and said bracket arm is interposed an expansion spring 45. Thus, the valve member 41 is mounted for rotation and the spring 45, reacting from the bracket arm 43 through the nut 44 and the stem 42, holds said valve member tightly against the outer face of the outer wall of the container 35. The valve member 41 is removably mounted upon the stem 42 to permit ready removal of the louver unit 29 whenever desired.

The support B is formed from rod or rod-like material and is of novel, endless form. It comprises a horizontal base portion composed of a pair of laterally spaced apart arms 46 joined together at their rear ends by a curved, transversely extending arm 47, and an upright portion composed of a pair of laterally spaced apart arms 48 constituting upward continuations of the arms 46 and joined together at their upper ends by a curved, transversely extending arm 49.

The fan proper comprising the air circulating unit A, the casing 22 and the elements contained in and carried by the latter, is disposed between and is mounted upon the arms 48 for

tilting adjustments in a vertical plane by means of a pair of pivot members 50 which extend from said arms through the sides of the casing and are suitably connected to the annular member 11. Said pivot members may, for example, be in the form of bolts extending through the arms 48 and threaded into the annular member 11, and between said arms and the casing 22 may be interposed suitable friction washers 51 to be placed in compression by tightening of said bolts to hold the fan proper in any desired position of tilted adjustment relative to the support B.

The support B may be formed from a single length of rod, tubing or the like or it may be composed of two or more sections of the same or different materials. For example, the base portion thereof, including the arms 48 upwardly short distances above the pivot members 50, may be formed from metal tubing, and the top portion thereof, including the upper portions of the arms 48 and their connecting portion 49, may be formed from plastic rod to enhance the attractive appearance of the fan. In any event, the connecting portion 49 extends over the fan proper and constitutes a handle for use in placing the fan in any desired position.

The switch 26 is of a known type such that the heating unit 16 may or may not be energized when the air circulating unit A is energized. Thus, the air circulated by the fan may or may not be heated, as desired. Likewise, the lamp 19 may or may not be energized as desired during operation of the air circulating unit A.

When the air circulating unit A is in operation, air is drawn from the space in the rear of the fan through the louver passageways *b* into the casing 22, flows forwardly through said casing and the tubular and the annular members 15 and 11 and is discharged through the flaring passageways *a* whereby it is diffused. In entering the casing 22 the air passes through the filtering element 33 and thereby is cleaned, and as it flows through said casing it may or may not be subjected to the action of the germicidal lamp 19, as desired. Moreover, the valve 41 may be adjusted to permit some of the air to flow through the container 35 to entrain vapor from the material contained in said container for air scenting, deodorizing or any other desired purpose.

As will be apparent, the present fan is of attractive appearance and all operating parts thereof are effectively housed and concealed from view.

From the foregoing description considered in connection with the accompanying drawings, it is believed that the construction and operation of the present fan will be clearly understood and its advantages appreciated. It is desired to point out, however, that while only a single structural embodiment of the invention has been illustrated and described, the same is readily capable of specifically different structural embodiments within its spirit and scope as defined in the appended claims.

We claim:

1. A portable electric fan comprising a casing open at its rear end for inlet of air thereto and open at its front end for outlet of air therefrom, means within said casing for circulating air therethrough, a louver unit at the rear end of said casing comprising a plurality of annular spaced apart members and a plurality of arms connecting them together, and detachable connections between said arms and said casing, said louver unit including a container for a vaporiz-

able material provided with openings to permit flow therethrough of part of the air circulated through said casing, and valve means for regulating flow of air through said container and for thereby regulating the amount of vapor entrained by the air circulated through said casing.

2. A portable electric fan comprising an open-ended annular member, a motor mounted in said member, an open-ended tubular member mounted upon said annular member and extending rearwardly therefrom in axial alinement therewith, a casing surrounding said annular member and said tubular member, blades driven by said motor for circulating air through said casing and said tubular member and said annular member, a bracket mounted in said tubular member, a container for a vaporizable material mounted upon the rear end of said casing and including rear and front walls having openings therein for flow therethrough of part of the air circulated by said blades, a valve disposed against the rear face of the rear wall of said container and movable to cover and uncover the openings therein to regulate the amount of air which flows through said container, a rod extending from said valve through said container and a portion of said bracket, and spring means cooperating with said rod and said bracket to hold said valve against the rear wall of said container.

3. A portable electric fan comprising an open-ended casing structure, a fan mounted in said casing structure for circulating air therethrough, a louver unit at the rear end of said casing structure through which air flows into said casing structure, said unit including a container for a vaporizable material having a wall provided with openings for flow of part of the fan-circulated

air through said container, a valve disposed against said wall and rotatably adjustable to regulate flow of air through said openings, and spring means holding said valve against said wall.

4. A portable electric fan comprising an open-ended casing structure, a fan mounted in said casing structure for circulating air therethrough, a container for a vaporizable material mounted upon said casing structure and including a wall having therein openings for flow of part of the fan-circulated air through said container, a valve disposed against said wall and movable to regulate flow of air through said container, a bracket in said casing structure, a rod extending from said valve through said bracket, and spring means cooperating with said rod and said bracket to hold said valve against said wall.
